ATTORNEY

UNITED STATES PATENT OFFICE.

EDWARD PHIPPS, OF HIGHLAND PARK, MICHIGAN.

MOP.

Application filed December 17, 1927. Serial No. 240,820.

The present invention relates to mops and has for its objects to provide a mop of novel construction providing a head to which the mop may be readily attached and disconnected at the will of the user.

Another object is to provide a mop head of such a character that the mop may be readily and thoroughly wrung out without the operator using his hands upon the mop or using other instrumentalities than those embodied in the instrument itself.

A further object is to provide a mop head, portions of which are adjustable relative to other portions for presenting the mop in various adjusted positions.

A further object is to provide a brush of such a construction that it may be used in connection with the mop head for certain special work.

Further objects are simplicity of construction, cheapness of manufacture and effectiveness in operation.

In the drawings constituting part of the present specification:—

Figure 1 is an elevation of a mop head in accordance with my invention showing the mop attached thereto.

Figure 2 is a view of the mop shown in Figure 1 looking at the same at right angles to the position shown in Figure 1.

Figure 3 is a view similar to Figure 1, but showing the mop head in somewhat different adjustment showing the mop in process of wringing.

Figure 4 is an enlarged section on line 4—4 of Figure 3 showing the construction of the handle of the mop.

Referring to the drawings in detail by reference numerals, 10 designates a handle having a cap 11 secured to its upper end, said cap being provided with outstanding arms 12 terminating in tubular members 13 having openings 14 formed on their upper sides. Slidably mounted upon the handle 10 is a sleeve or ferrule 15 having arms 16 extending laterally and then upwardly as shown in Figure 1, the upwardly extending portions preferably spreading slightly apart toward their upper ends and having attached thereto a tubular member 17 similar to the tubular members 13 above described which is provided on its upper side with an opening 18, said openings 14 and 18 extending the full length of the tubular members. The handle 10 is provided with longitudinal

grooves 19 adjacent one end as shown and the ferrule 15 is provided with a latch device 20 pivotally mounted thereupon as at 21, and having a pin 22 secured to one end thereof and adapted to be extended through an aperture 23 in the ferrule and into one of the grooves 19 in the handle. The pin 22 is normally held in position in the groove by means of a spring 24 exerting a pressure between the ferrule and the member 20 as shown in Figure 2. Holes 25 are provided in the handle with which the pin 22 is also adapted to co-operate to hold the mop in fixed position. The member 20 is preferably oval-shaped and is formed substantially in the shape of a spoon having the concaved side toward the ferrule and the pivotal means 21 located centrally of the hole thereof. The mop members 26 are secured in the tubular members 13 and 17 by means of pins 27 which are inserted therein after the material of the mop has been previously placed therein, the mop material being looped about the pins and lying between the pins and the walls of the tubular members 13 and 17. The pins are preferably provided at one end with heads 28 to prevent their sliding too far into the tubular members.

The operation of my invention is as follows: When it is desired to use the mop in the ordinary manner, the mop is attached to the head by first inserting the mop material through the openings in the tubular members 13 and 17 and then inserting the pins therein to bind the material in position. The ferrule 15 is then slid to a position which will give a free grouping of the mop materials for mopping purposes and the mop is then dipped in water in the usual manner and applied. When it is desired to wring the mop, the lever 20 is pressed upon overcoming the resistance of the spring 24 and lifting the pin out of engagement with the handle. The arms 16 may then be revolved about the handle twisting the mop in the manner as shown in Figure 3. When so twisted, a longitudinal movement may be given the arm 16 thereby further squeezing the water out of the mop. The mop may then be adjusted as above and the mopping operation continued.

When special work is desired as on rough floors where a mop would become entangled in splinters and the like, a brush may be attached to the tubular member 17.

Having described my invention which I claim is:—

1. A mop comprising a handle, a ferrule mounted for slideable movement on said handle, arms formed with said ferrule, a tubular clamp formed with the outer ends of said arms, tubular clamps secured to the outer end of said handle and cooperating with the clamp first mentioned for receiving 10 mop fabric, a locking pin for each clamp for securing the fabric therein, a spring latch carried by the ferrule and a detent included in the latch and adapted to be received in the grooves and holes in the handle for securing the clamps of the arms in various 15

relative positions with respect to the clamps of the handle.

2. A mop comprising a handle, a ferrule mounted for slideable movement thereon, arms having one of their ends formed with 20 said ferrule, a tubular holder formed with the opposite ends of said arms, tubular holders carried by the handle, removable pins in said holders for securing mop fabric thereto, and a spring latch carried by said 25 ferrule to lock the latter and its arms against turning.

In testimony whereof I affix my signature.

EDWARD PHIPPS.
